PREFORMED WELT FOR BOOT AND SHOE CONSTRUCTION

Wallace C. Wright, Brookfield, N. H.

Application January 18, 1941, Serial No. 374,994

1 Claim. (Cl. 36—78)

My present invention is a novel and improved pre-formed welt for use in the manufacture of boots and shoes, employing a welt in the construction of the same.

The present application is a continuation in part of my prior and copending application 357,293, filed September 18, 1940, on "Shoe, welt therefor, and process of making," wherein I have illustrated, described, and claimed the advantages incident to a welt made of synthetic or plastic material, wherein a pre-curved or pre-formed welt structure, both widthwise and lengthwise, or both, is advantageously produced.

My present invention is directed to the pre-forming or pre-curving widthwise of a welt formed of leather, laminated strips of leather, canvas, or the like material, as distinguished from synthetic plastic material. I have discovered that it is feasible to thus pre-form welt strips for better inseaming and outseaming, and that this advantage in my pre-formed welt structure is equally suitable for standard shoe method of construction, wherein the upper materials are lasted over the insole and then the welt attached to the insole and upper, or to "pre-welt" methods, wherein the welt is first attached to the upper and then lasted.

An important advantage and feature of this pre-forming construction, particularly in the pre-forming widthwise of the welt material, is that the outer edge portion of the welt and the adjacent part of the outsole will normally tend to be tightly united in contact, particularly during the outsole-attaching operations and wherein the outsole is cemented to the shoe bottom prior to the outsole stitching.

Thus, instead of the welt normally tending to be forced upward and away from the outsole, by means of my pre-forming widthwise processes the outer edge of the welt is normally tending to hub the adjacent edge of the outsole entirely around the margin of the shoe. This is particularly important and advantageous at the shank and toe portions of a shoe. While it is also feasible to pre-form such a welt lengthwise as well as widthwise, giving a natural "spring" or curve for better fitting around the toe, the more important pre-forming is the widthwise curvature, which can be put in at any angle, arc, or bend desired for the particular type of shoe to which my pre-formed welt is to be applied.

I also have devised a novel method of so pre-forming such a welt, which consists preferably in first tempering the welt and then forcing it continuously thru forming rolls, wheels, or dies,

which will give the desired lengthwise contour to the welt.

Referring to the drawing illustrating preferred embodiments:

5 Fig. 1 is a fragmentary view in perspective of my improved welt of a typical widthwise pre-formed contour;

Fig. 2 is a cross-sectional view of the same;

10 Fig. 3 is a fragmentary cross-sectional view illustrating the process of welt attaching during the inseaming;

Fig. 4 is a similar cross-sectional fragmentary view illustrating the attachment of the outsole;

15 Fig. 5 illustrates a pre-welt attaching method, and

Fig. 6 is a diagrammatic view partly in cross-section showing the pre-forming process.

As shown in the drawing, my pre-formed welt consists first of a welt strip of suitable width, thickness, and length for use as a welt, wherein the same has been pre-curved or pre-formed widthwise, producing an outsole-attaching portion 1, an inseam attaching portion 2 at an angle therewith, joined by an intermediate curved or bent section 3, and wherein a stitch-receiving groove 4 is cut. This structure enables the portion 2 to be more snugly, evenly, and smoothly fitted to the curved contour of the shoe upper during the inseam sewing operation.

30 Furthermore, by my pre-forming construction, the stitch-receiving groove 4 normally tends to enclose the inseam stitching 5 when the same is applied. I contemplate the utilization of a simple plow, or the like, to open the stitch-receiving groove 4 during the inseaming operation, in which case the portion 1 of the welt would be raised substantially as shown in dotted lines, Fig. 3, whereupon the welt will normally spring back into its pre-formed contour ready for attachment of the outer edge portion 1 to the outsole, after the usual trimming operation.

I have illustrated this process in Fig. 3, wherein a shoe last 10 has the insole 11 applied to the last bottom with a sewing rib 12 to which the upper materials 13 and 14 are lasted and secured by the inseam stitching 5. During this inseaming operation, it will be appreciated that my pre-formed welt with the curved portion 3 fitting snugly in under the overhanging part of the insole, last, and upper materials, particularly around the shank and forepart, will enable the inseam stitching 5 to be more easily and snugly applied and give a tighter fitting of the shoe at this point.

After the rib 12, projecting marginal portions

13 and 14 of the upper materials, and a part of the welt 2 are trimmed approximately along the dotted line 15, Fig. 3, the filler 16 applied, and the outsole 20 secured by outseam stitching 21, a better fitting of my pre-formed welt will be readily appreciated.

In Fig. 5 I have illustrated my pre-curved or preformed welt structure as being first attached to the upper materials by straight line stitching 22, whereupon the welt is then used by lasting devices to work over the marginal portion of the upper onto the insole, giving an equally beneficial welt shoe construction.

In Fig. 6 I have illustrated diagrammatically a simple method of pre-forming widthwise the welt strip. For this purpose, a suitable pair of forming rolls 30 and 31, mounted on rotatable axles 32 and 33 respectively and rotated from any suitable source of power, are fitted to interlock and conform the welt strip therebetween.

I have illustrated in Fig. 6 both the welt and these rolls of enlarged size. The welt strip being of suitable temper with the groove 4 formed therein, and the welt in long flat strips, the welt is fed thru the forming rolls 30 and 31 under suitable pressure and with heat, if desired, to more quickly and readily "set" the curved or pre-formed contour imparted to the welt by the rolls.

I have shown in the roll 30 an internal recess 35 in one of the flanges 36 in which the corresponding curved edge 3 of the welt is conformed, the other flange 37 of the roll 30 cooperating with the corresponding edge of the lower roll 31 to hold the portion 1 of the welt in desired position relatively with the other edge portion 2, substantially as shown.

Such leather employed for welt strips is usually of a high grade and of strong texture to hold the inseam and outseam stitching, and under suitable heat and pressure, and particularly while in temper, can thus be readily and perma-

nently set to substantially the widthwise contour imparted to it by the forming rolls. If desired, these rolls can "over-bend" the portion somewhat, allowing for a slight rebound of the strip.

Also I may, if desired, treat the welt strip with a solution, binder, or the like which will still further tend to hold the welt in the pre-formed and curved condition imparted to it by the rolls or equivalent devices.

The widthwise curve showing in the drawing is, of course, illustrative only and any desired contour can be secured, and other devices utilized than the rolls.

My pre-formed welt gives not only a better and snugger fitting of the stitch-receiving edge portion of the welt, enabling this portion to fit snugly in underneath the overhanging insole feather, but also eliminates largely or entirely the necessity of the former welt-beating operation, since my pre-formed welt normally tends to spring horizontally and thus to contact firmly with the margin of the attached outsole.

I claim:

As a new article of manufacture, a permanently pre-formed welt for use in the manufacture of welt boots and shoes, said welt having incorporated therein a binding element aiding in maintaining it in said pre-formed condition; said welt having a longitudinal stitch-receiving groove cut therein and being bent in a pre-formed angular position about the base of said groove, said angle being greater in extent than the normal angle to which the welt is bent in the completed shoe, said bend normally acting to substantially close the open edges of said stitch-retaining groove and automatically closing after the inseaming stitching is applied in said groove, thereby protecting and enclosing said stitching, and the longitudinal welt bend normally forcing the outer welt edge against the outer edge of the outsole to be permanently united thereto.

WALLACE C. WRIGHT.
